[57] CLAIM

The ornamental design for a surveillance camera housing, as shown and described.

DESCRIPTION

FIG. 1 is a front and bottom right perspective view of a surveillance camera housing showing my new design; FIG. 2 is a rear and top right perspective view thereof; FIG. 3 is a front and bottom right perspective view of another embodiment of my new design of FIGS. 1-2; FIG. 4 is a rear and top right perspective view thereof; FIG. 5 is a front and bottom left perspective view of both embodiments as mounted on a ceiling or other flat surface. The broken-line showings are environmental only and form no part of the claimed design. The characteristic feature of the design illustrated in the drawing resides in the external appearance of the camera housing when it is mounted on a ceiling or other flat surface, as shown in FIG. 5.
